UNITED STATES PATENT OFFICE.

WILLIAM J. WHITE, OF PHILADELPHIA, PENNSYLVANIA.

CLOTHESLINE-SUPPORTING DEVICE.

Application filed May 29, 1922. Serial No. 564,298.

One object of my present invention is to provide an improved clothes line supporting device which can be readily erected in a yard of a dwelling so that after the clothes 5 are secured to the lines they can be raised to such height that persons or vehicles can freely pass thereunder without touching the clothes. Owing to my improved construction, the device is of particular advantage 10 for use in the yards of homes having garages so that automobiles can pass through the yard to and from the garage even though clothes are hanging on the device.

Another object is to make my improved 15 device of a durable construction which can be cheaply and quickly manufactured and which can be readily operated to raise and lower the clothes while on the lines.

Another object is to provide an improved 20 and simplified construction embodying a transverse beam prop which will be operative when the lines are raised to support and slightly elevate the lines between their ends and which, when the lines are lowered, 25 will be moved downward to allow the clothes to be readily removed from the lines.

These objects, and other advantageous ends which will be described hereinafter, I 30 attain in the following manner, reference being had to the accompanying drawings in which—

Figure 1 is a front elevation of a device made in accordance with my present invention,

Figure 2 is a cross sectional elevation of 35 said device showing the lines lowered,

Figure 3 is a view of the same general character as shown in Figure 2 illustrating the lines raised,

Figure 4 is an enlarged fragmentary section partly broken away; the section being taken on the line 4—4 of Figure 3,

Figure 5 is an enlarged fragmentary inverted plan view of certain of the parts,

Figure 6 is an enlarged fragmentary section taken on the line 6—6 of Figure 2,

Figure 7 is a face view of one of two supporting carriages which I employ,

Figure 8 is a top plan view of said carriage, and

Figure 9 is a perspective view of a securing corner channel angle which forms a part of my invention.

Referring to the drawings, my improved 55 device includes a main supporting frame 10 having two posts 11 and 12 which are made

of channel metal with their lower ends embedded within the ground 13 preferably by forming a pedestal of cement or concrete in which the lower ends of the posts are embedded; said cement extending into the ground 13. These posts 11 and 12 have their hollow channel spaces opposed to each other and at their tops are provided with corner channel angles 15 and 16; a detail of 60 one of these angles being shown in Figure 9.

The lower legs of these channel angles embrace the tops of the posts 11 and 12 and the top or horizontally extending legs of the channel angles embrace opposite ends of a top channel 17. Bolts 18 and 19 extend through registering holes in the top channel and posts 11 and 12 and serve to secure the top channel to the tops of the posts. The 65 posts and top channel are made of metal of sufficient strength as to form a rigid frame 70 capable of supporting itself in the position shown in Figure 1.

I provide two similarly constructed line connecting carriages 20, each of said carriages including a frame 21 having a plate portion 22 with side flanges 23 which are arranged parallel; the flanges 23 having extensions 24 which are spaced apart in the direction of the height of the carriages; said extensions at the top and bottom of the carriages being connected by integral cross portions 25. These extensions form bearings 75 for rollers 26; the peripheral surfaces of the rollers being spaced outwardly from the surface 27 of the plate portion 22 of each carriage, as clearly shown in Figure 4. The opposite surface of the plate portion has a ledge 28 and above the ledges 28 on each of the carriages is secured an angle bar 29; said bars being attached to the plate portions of the carriages by bolts 30. The lower 80 legs of the bars 29 have holes 31 spaced apart and within these holes are adapted to be hooked the ends 32 of S-hooks 33. The opposite ends of the S-hooks have the ends 85 of clothes lines 34 attached thereto; said clothes lines being of such length when attached to the hooks 33 as to extend from one carriage to the other when the carriages are mounted on the posts with the posts between the rollers 26 and the surface 27 of the carriages. In fact the clothes lines 34 are made 90 of such length that when thus attached they will be slack so that when not otherwise supported, they will bow slightly downward as shown in dot-and-dash lines in their

100

105

110

lowered position as illustrated in Figure 1.

Stop members 35 in the form of strips which are secured to the posts 12, serve for abutment with the lower extensions 24 of 5 the carriages 20 to limit the downward movement of said carriages such for example as shown in dot-and-dash lines in Figure 1.

For the purpose of elevating the lines 34 10 from the dot-and-dash line position to the full line position shown in Figure 1, I provide the following hoisting mechanism: A yoke member 36 includes side flanges 37 which are bolted to the sides of the post 12; 15 said yoked member as clearly shown in Figure 6 including a transversely extending portion 38 which is opposed to the part 39 of the post 12. A winding drum 40 has its opposite ends rotatably mounted in the 20 portions 38 and 39 and the winding drum has an angular spindle 41 to which is secured a lever 42; said lever having an angular hole 43 through which the angular spindle 41 extends. A cotter pin 44 or 25 other suitable means can be employed to prevent the lever from accidentally sliding off the spindle. The spindle 41 has a ratchet wheel 45 attached thereto and the portion 30 of the member 36 has a pawl 46 pivotally connected therewith; said pawl having a part 47 adapted to engage the ratchet wheel 45 and lock the drum 40 against rotation.

The drum 40 has one end of a cable 48 secured thereto and the other end of said cable is connected by means of a triangular link 49 with two other cables 50 and 51 as clearly shown in Figure 3. The cable 50 extends upward within the channel space 40 of the post 12 and passes over a pulley wheel 52 in a pulley block 53; said pulley block being swingably supported by an eye connection with the bolt 18 at the top of the post 12. The opposite end of this cable 50 extends downward from the wheel 52 and 45 is connected to an ear 50^a of the carriage 20 which is mounted on the post 12. The other cable 51 passes upwardly through the channel space of the post 12 and over a pulley wheel 54 in the pulley block 53. The cable 51 then extends horizontally under the channel space of the top channel 17 and passes over a wheel 55 in a pulley block 56 and then downward within the channel 50 space of the post 11 and is secured to an eye 51^a of the carriage 20 which is mounted on the post 11. The pulley block 56 is swingably mounted on the eye connection with the bottom of the bolt 18 of the corner channel angle 15 as clearly shown in Figure 4. 60 It will thus be noted with the construction already described that by turning the lever 42, the carriages and lines 34 can be raised when the lever is turned in one direction or can be lowered due to their weight when 65 the lever is turned in an opposite direction;

it being noted that the bars 29 have their lower leg portions in planes passing horizontally between the rollers 26 of each carriage so that said rollers will provide anti-friction means and even though the weight 70 on the lines 34 is considerable there will be very little friction between the carriages and the posts.

The cable 51 includes a link 57 within its length and to this link are attached two other cables 58 and 59. These cables pass over pulley wheels in pulley blocks 60 and 61 respectively which are in flexible connection with eye bolts 62 which are secured to the sides of the top channel 17 preferably 80 at a position midway between the posts 11 and 12.

Thus the pulley blocks 60 and 61 can swing on the eye bolts 62 for a purpose herein-after rendered obvious. The cables 58 and 59 extend at diverging angles downwardly from the pulley blocks 60 and 61 and are secured adjacent the opposite ends of a horizontal prop 63; said prop extending under all of the lines 34. It will be noted that when the lines 34 and prop 63 are in their lowermost positions, as shown in Figure 2, that the cables 58 and 59 will extend upward at an acute angle to each other as shown in Figure 2; the arrangement, when the lines and prop are elevated, requiring that the angular disposition of the cables 58 and 59 be more obtuse when said lines and prop are raised as shown in Figure 3. This variation of the angle will cause a difference in the extent of movement between the carriages and the prop 63 so that when the carriages and prop are raised the prop will move a greater height and lift the lines 34 between their ends as shown in full line positions in Figures 1 and 4. On the other hand, when the lines and prop are lowered, the prop will move to such level as to allow the lines to sag downward to facilitate the attachment of clothes thereto. To attain this difference in the extent of movement of the prop, the pulley blocks 60 and 61 by being connected directly to the opposite sides of the top channel are much closer together than the points of attachment of the lower ends of the cables 58 and 59 to the prop.

By attaching the lines 34 by the S-hooks, it is an easy matter to remove or replace any of the lines since it is merely necessary to unhook the structure from the holes of the bars 29.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A clothes supporting device including posts; a clothes line; a carriage movably embracing each post, each carriage being provided with a plate part having a ledge; an angle bar for supporting the clothes line resting on the ledge and secured to the plate part, and means for raising the carriages on the posts.
- 10 2. A clothes supporting device including

posts; a clothes line; a carriage movably embracing each post, each carriage being provided with a plate part having a pair of 15 extensions on each side integral with the plate, cross portions connecting the extensions and rollers rotatable in the extensions; angle bars for supporting the clothes line secured to the plate part, and means for rais- 20 ing the carriages.

In testimony whereof I have signed my name to this specification.

WILLIAM J. WHITE.
